UNITED STATES PATENT OFFICE.

GEORGE H. CLARKE AND CHAS. VAN WAGENEN, OF NEW YORK, N. Y.,
ASSIGNORS TO GEORGE H. CLARKE, OF SAME PLACE.

GRATE-BAR.

Specification forming part of Letters Patent No. 59,311, dated October 30, 1866.

To all whom it may concern:

Be it known that we, GEORGE H. CLARKE and CHARLES VAN WAGENEN, of the city, county, and State of New York, have invented a new and useful Improvement in Grate-Bars for Furnaces; and we do hereby declare the following to be a full, clear, and exact description thereof, reference being had to the accompanying drawings, figures, and letters of reference thereon, making part of this specification, in which—

Figure 1 is a top view. Fig. 2 is a side elevation, and Fig. 3 an end view.

Similar letters of reference indicate like parts in all the drawings.

In most of the grate-bars heretofore made and used no practical arrangement has been made by which a bar located in the center or at a distance from the side could be unlocked and removed without commencing at the side and removing all the bars until the defective one was reached, so that it could be removed readily.

Our invention is designed to obviate this difficulty, and also to better provide for expansion of the bars when heated; also, in so arranging the bars that the fires may be readily removed when desired, as will be fully set forth hereinafter.

A represents the middle bar of three, to which the bars B and C are secured by supports *a a*, as shown. The bar A is cast with an arched base to strengthen and support the bar. On the bars B and C are cast vertical dovetails *c c*, by which each set of bars is interlocked and retained together in proper position.

The supports *a a* at the ends of the bars are cut at *b*, to admit of expansion. These cuts *b b* are cast in the bars by inserting in the mold a strip of metal, which is readily removed after the bar is cast.

To rake or draw the fire quickly when desired we cut away a portion of the supports *a a*, as shown at *d*, so that the upper surface of these supports shall be somewhat below the planes of the surface of the bars A B C, so that the rake-teeth shall not be obstructed in drawing the fire from the bars.

In the manufacture of grate-bars we effect a great saving of time by casting three bars together, and providing for their unequal expansion in use and the ready removal of any bar from the furnace, and the substitution of another in its place, without regard to the position of said bar in the set. One or more of the supports *a a* may be cut as shown, to provide for expansion of the bars.

Having thus fully described our invention, what we claim, and desire to secure by Letters Patent, is—

In combination with the arched bar A, the bars B and C, provided with vertical dovetails or similar interlockments, the slotted ends dividing the bars to admit of longitudinal expansion, and the grooves or depressions in the supports *a a*, the whole constructed substantially as described, and for the purposes specified.

GEORGE H. CLARKE.

CHARLES VAN WAGENEN.
